APPARATUS FOR PRINTING TENNIS BALLS

Cuyler S. McChesney and Michael Lukacz, Jr.,
Kenmore, N. Y., assignors to Dunlop Tire and
Rubber Corporation, Buffalo, N. Y., a corpora-
tion of New York

Application March 30, 1937, Serial No. 133,782

6 Claims. (Cl. 41—1)

Our invention relates to an apparatus for printing tennis balls as, for example, printing them with a trade-mark.

The surface of the fibrous covering of Melton cloth with which tennis balls are covered rapidly wears away when the ball is in play and, accordingly, the trade-mark or other printed matter on this surface soon becomes illegible, or vanishes with the surface.

10 In our present invention this rapid disappearance of the printed matter, or its legibility, is avoided by causing the printing material to sink inwardly from the surface of the cloth to a depth that remains after considerable wearing away 15 of the fibrous material at the surface.

Our invention, therefore, provides an apparatus by which the surface of a tennis ball may be brought into contact with a printing die having sufficient of the coloring material and for 20 a sufficient time to cause the material to sink deeply into the cloth wherever an impression is made. Preferably, the printing material comprises a coloring material dissolved in a wax or waxy composition of high melting point which, 25 during printing, is heated to render it fluid at those points of contact with the tennis ball surface at which the color is to be applied. The invention also provides a transfer strip carrying a relatively large proportion of the printing 30 composition and capable of impressing the tennis ball with sufficiently fine detail.

The various features of the invention are illustrated, by way of example, in the accompanying drawings, in which—

35 Figs. 1 and 2 are, respectively, side and plan views of an apparatus for impregnating or forming the transfer strip for printing.

Fig. 3 is a plan view, and Fig. 4 a side elevation, of a machine for printing tennis balls.

40 Fig. 5 is a vertical sectional view taken on the line 5—5 of Fig. 3.

Fig. 6 is a front view of elements for transferring a design to a ball.

Fig. 7 is a section on line 7—7 of Fig. 6.

45 Fig. 8 is a plan view of the mechanism shown in Fig. 6, partly in section, on line 8—8 of Fig. 6.

Fig. 9 is a front view of a printing plate.

Fig. 10 is a view of a completed ball of our invention.

50 In our invention a design is printed from a transfer strip to the surface of a tennis ball by pressing a heated printing element against the transfer strip and forcing the latter into contact with the surface of the ball. The contact strip is made of a fabric capable of holding

a relatively large quantity of a colored wax composition, rayon being a suitable fabric for this purpose. Any suitable wax may be employed but, preferably, one of high melting point. A wax consisting of 85 parts carnauba wax (No. 1 yellow), 6 parts of stearic acid (triple pressed), 7 parts of paraffin, and 2 parts of a suitable color, such as Victoria Blue (B base), or other color soluble in the wax is suitable for this purpose. The transfer strip may be made and renewed 10 by passing it through a molten mixture of the wax and removing excess therefrom.

In printing a tennis ball, the transfer strip is drawn from a take-off roll to a wind-up roll between a heated printing plate and a ball holding and positioning element. During each printing cycle the ball and the printing plate are forced toward each other so as to heat and press the transfer strip against the ball wherever the color is to be transferred.

20 The ball and printing plate are held in this position for a timed interval sufficient to permit the colored wax to sink deeply into the fibrous Melton cloth. Thereupon the ball and printing plate are withdrawn, the ball replaced by a succeeding one, the transfer strip moved to expose a new area to the printing operation, and the process repeated. Preferably, there are timed intervals in which a ball may be removed and replaced and in which the printing plate and ball 25 are pressed against opposite sides of the transfer strip.

25 Referring more particularly to Figs. 1 and 2, a strip or strips 11 of rayon, or other suitable fabric, to be impregnated with the colored wax 30 are drawn from their respective reels 12 mounted on a suitable frame 13 into a bath 14 of colored wax composition maintained molten by an electric heating coil 15. Three strips are illustrated 35 in the drawings as being waxed in a single path simultaneously, but it will be understood that the apparatus may be made to accommodate one or any number of strips at a time by providing a suitable number of reels. In passing through the bath 14 the strips 11 are drawn beneath a 40 pair of rods 16 and 17 and then passed outwardly and alternately over and under a number of supporting rods 18, 18', 19, 19', 20, 20', 21, 21' and 22 to a pair of pull rollers 23 and 24 journaled in the frame 13 and having intermeshing 45 gears 25. One of the pull rollers 24, for example, is driven by a motor 26 through a belt 27 which is trained over a pulley 28 keyed onto the shaft of the roller 24. As the transfer strip leaves the molten bath 14, excess wax is scraped 50

from one side by the first rod 18. The wax composition given by way of example above will be in molten condition at 95° to 100° F., and the bath is kept at this temperature.

- 5 By the time the strips reach the rolls 23 and 24 the wax will have cooled and solidified sufficiently to remain in position on the strips. From the rolls 23 and 24 the strips then pass about a horizontal rod 29 and thence to respective take-up reels 30. The take-up reels 30 are driven from a group of grooved pulleys 31 on the shaft of the roll 24 by means of belts 32 which are trained about grooved pulleys 33 on the respective shafts of the take-up reels 30. There is a sufficient slippage between the belt and the grooved pulleys 33 so that the take-up reels 30 do not exert a pull on the pull rolls 24 much in excess of that required to roll up a strip as it leaves the pull rolls.
- 20 Referring to Figs. 3 to 8 inclusive, in printing the tennis balls from the transfer strip 11 waxed as illustrated in Figs. 1 and 2, the strip is drawn from a let-off reel 34 about a guide pulley 35, thence through a printing mechanism 36 by an indexing roll or pulley 37 and pressing roll 38, and then wound up on a take-up reel 39. The printing mechanism 36, as shown more particularly in Figs. 6, 7 and 8, comprises a registering block 40 having an opening fitting the curvature 30 of a ball 41 to be printed, a pressing lever or finger 42 to press the ball into the spherically curved surface of the registering block 40, and a heated printing plate 43 to be brought against the spherical surface of the ball extending 25 through the recess in the registering block 40.

The strip 11 is drawn into position between the registering block 40 and the printing block 43 so that the raised parts on the printing block will press the transfer strip into engagement with the 40 surface of the ball 41. The printing block 43 is heated by an electric coil 44 to melt the colored wax and cause it to sink in and penetrate the covering fabric of the ball. The movements of the printing block and of the finger 42 are controlled by a motor of substantially constant speed 45 which, in each revolution, opens a valve during a predetermined cycle of the revolution, and closes it during the remainder of the cycle. When the valve is opened, it admits fluid pressure, or other motive means, to drive the printing block and the ball to be printed into contact through the transfer strip and to hold them in tight engagement throughout the cycle, and then to release them and permit the ball to be replaced by 50 another, and a new length of transfer strip to be drawn into position.

In Figs. 3 and 4 the timing mechanism is driven by a substantially constant speed motor 45 which is connected through a coupling 46 and speed 60 reduction mechanism 47 to a drive shaft 48 which carries a drive pulley 49 and a timing cam 50. As shown in Fig. 4, the cam 50 comprises a segment of a circle and during a certain part of the rotation of the shaft 48 engages and presses a stem 51 of a valve 52 to open the valve.

When the valve 52 is opened, fluid under pressure passes from the main 53 through pressure reducing mechanism 54 and branch pipe 55 through the valve and to a pipe 56 leading to 70 one side of the diaphragm of a diaphragm control valve 57. Upon the admission of fluid pressure to the diaphragm valve 57, the valve stem 58 of the latter is pushed downwardly. Pressure fluid is supplied from the reduction mechanism 54 through pipe 59 to the valve chamber 60 of

the valve 57, and when the valve stem 58 is depressed, the valve member 61 is in position to admit air from the pipe 59 to a pipe 62 leading to the right hand end of an air cylinder 63. Simultaneously, the pipe 64 leading from the opposite end of the cylinder 63 is put into communication with an exhaust pipe 65. The pressure fluid admitted to the cylinder 63 forces a piston 66 to the left in the position shown in Figs. 4 and 5. This piston 66 has a piston stem 67 carrying on its free end a crosshead 68 to which is bolted the printing block 43. This movement of the piston 66, therefore, carries the printing block 43 toward engagement by a ball 41 in position in the registering block 40. The crosshead 15 68 has a depending bracket 70 which is connected by means of a link 71 with the vertical lever 42 pivoted at 73 in a bracket 74 of the frame of the machine so that as the crosshead moves toward one side of the ball 41, the upper part 20 of the lever 42 presses the ball from the opposite position. The upper end of the lever 42 is curved, as at 75, to fit the curvature of the ball 41. In this way the printing block and the ball to be printed are pressed equally from opposite directions against opposite sides of the transfer strip.

When the cam 50 moves out of contact with the valve stem 51, the latter is moved to close the passage of fluid from the pipe 55 to pipe 56 and to open the latter to the atmosphere, whereupon 30 the valve stem 58 and valve element 61 move upwardly. Thereupon the pressure fluid supply pipe 59 is brought into communication with the pipe 64 and the pipe 62 is brought into communication with an exhaust pipe 76. Accordingly, fluid 35 pressure admitted through the pipe 64 forces the piston 66 to return to its original position. It remains in this position until the cam 50 again comes into contact with the valve stem 51. The crosshead may be guided in its movements by a 40 pair of guide stems 77 mounted in a frame 78 that carries the register block 40.

While the printing block 43 and upper part 75 of the lever 42 are in their withdrawn separated positions, the printed ball may be removed and 45 placed on a receiving tray 79 and replaced with a new ball to be printed in a succeeding cycle. During this interval also, the roller or pulley 37 may be indexed to draw a succeeding fresh length of the transfer strip into printing position. 50 For this purpose a ratchet 80 is provided on the roll 37 in position to be engaged by a pawl carried on a manually operable lever 81. To index a fresh length of strip into printing position the lever 81 is moved counter-clockwise a sufficient 55 distance. The strip being pressed against the roller or drum 37 by the pressure of the roller 38 which is pivotally mounted on a swinging lever 82 and pressed by a spring 83, serves to draw the length of strip past the printing position. 60

The take-up reel 39 is driven from the pulley 49 by means of a belt 84 which passes with light friction about a pulley 85 keyed onto the shaft 86 of the reel 39, and returning over an idler 87. The belt 84 has sufficient slippage on the 65 pulley 85 so that it has only sufficient force to take up the slack in the strip between the indexing pulley 37 and the reel 39 and thus causes the reel to wind up the strip.

With the above method and apparatus the application of heat and pressure from the printing block through the transfer strip to the surface of the ball may be regulated so that the wax may have time to penetrate deeply into the fabric. That is, it may penetrate not only through the 75

felts fibers but even, to some extent at least, into the warp and woof of the covering fabric. Consequently, the design or mark will remain visible a much longer time than in the ordinary 5 printing method and apparatus. Also, the rayon transfer strip enables more wax to be carried and, therefore, provides an ample supply for penetration than would be the case if the usual paper strip were employed.

10 What we claim is:

1. Apparatus for printing the surfaces of fabric covered balls which comprises a printing block, means for heating said printing block, a register block, means for passing a transfer strip at successive intervals progressively between said printing block and said register block, and means to move said printing block toward said transfer strip and said register block and hold it thereagainst for predetermined timed intervals between each movement of said transfer strip.

2. Apparatus for printing the surfaces of fabric covered balls which comprises a printing block, means for heating said printing block, a register block, means for passing a transfer strip in successive progressive steps between said register block and said printing block, and timed means to move a ball to be printed against said register block on one side of said transfer strip and to move said printing block against the surface 20 of said ball from the other side of said transfer strip and hold them in this position for a predetermined part of each cycle and then return them to their original position.

3. The apparatus of claim 2 in which said means to move a ball against said register block comprises a lever to engage a ball, a link to swing the ball engaging part of said lever in the

opposite direction to the movement of said printing block, a rotating timing element, and a motor to move said printing block to and from printing position at definite timed intervals.

4. Apparatus for printing the surfaces of fabric covered balls which comprises a printing block, means for heating said printing block, a register block, a transfer strip between said printing block and said register block, a fluid actuated piston for moving said printing block to and from said transfer strip, a lever having one arm to engage a ball and a link connecting the other arm to said printing block whereby the ball engaging arm and printing block move in opposite directions, and cyclicly operating means to admit 10 pressure fluid alternatively to opposite sides of said piston at predetermined timed intervals.

5. The apparatus of claim 4 in which said cyclicly timed means comprises a rotating cam, a valve actuated to be opened and closed by said 15 cam, and a diaphragm valve controlled by the opening and closing of said first mentioned valve to direct pressure fluid alternatively to opposite sides of said piston.

6. Apparatus for printing the surfaces of fabric covered balls which comprises a printing block, means for heating said printing block, a register block, a transfer strip between said printing block and said register block, means for moving said printing block to and from said transfer strip, 20 a lever having one arm to engage a ball and a link connecting the other arm to said printing block whereby the ball engaging arm and printing block move in opposite directions.
